(57) **CLAIM**

The ornamental design for a rotary insect deterrent, as shown and described.

DESCRIPTION

FIG. 1 is a top, rear, right side, perspective view of a rotary insect deterrent;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof;

FIG. 7 is a bottom plan view thereof; and

FIG. 8 is a bottom, front, right side perspective view thereof; and,

FIG. 9 is a close-up of a portion of the vortex design shown in FIG. 2.

The evenly spaced broken lines shown in the drawings depict portions of the rotary inset deterrent that form no part of the claimed design. The dash-dot broken lines in FIG. 2 depict the limits of the enlarged view as shown in FIG. 9 and which form no part of the claimed design.
